UNITED STATES PATENT OFFICE.

DAVID S. BERNSTEIN, OF EVANSVILLE, INDIANA.

POCKET.

1,146,685.

Specification of Letters Patent. Patented July 13, 1915.

Application filed November 25, 1914. Serial No. 873,995.

To all whom it may concern:

Be it known that I, DAVID S. BERNSTEIN, citizen of the United States, residing at Evansville, in the county of Vanderburg and State of Indiana, have invented certain new and useful Improvements in Pockets; and I do hereby declare the following to be a full, clear, and exact description of the invention, such as will enable others skilled in the art to which it appertains to make and use the same.

This invention relates to apparel, and more especially to pockets having features of safety so that the contents may not be lost out; and the object of the invention is to produce four pockets in one, all of them being angular and two of them triangular. As far as my experiments have gone, the invention finds its greatest utility as a pocket for overalls, and I have successfully applied it to the apron which rises at the front of a pair of overalls. Hereon its safety features become extremely useful, because the working man so often stoops over during his labors that he frequently loses things out of his overall pockets. Again, as this garment is usually worn over the trousers which latter themselves have pockets wherein he carries things of greater value and rare use, the overall pocket or pockets are utilized for his ruler, his pencil or pencils, perhaps matches or coins, and other little articles which he may often need—yet does not care to withdraw from his trousers pockets while his hands are soiled. Finally the nature of the average laboring man's work is such as to cause him to often lie prone upon the floor or ground or to lean up against some object, and he might crush things in most pockets; also he frequently stoops, and might lose things out of the ordinary pocket as has been suggested and the result is that overalls usually have but a single pocket placed at a safe and accessible point. By my present invention this pocket is divided into a number of compartments best adapted in shape and disposition for the articles which are in all probability to be carried therein, due regard being had for the features of safety suggested.

The details of the invention will be found in the following specification and claims, and are illustrated in the accompanying drawings wherein:—

Figure 1 is a front elevation of a pair of overalls with one of my improved pockets applied to its apron, and Fig. 2 is an enlarged elevation of the pocket itself, stitched to any piece of cloth.

In Fig. 1 the letters L designate the legs of a pair of overalls which reach up to a waist-band W, A is the apron rising from this waist-band and having a middle upright seam M, S are the suspenders usually employed, and B designates a buckle. In Fig. 2 I have used the same letter A to designate any piece of cloth to which the pocket is sewed or attached by suitable means.

The pocket forming the subject-matter of this invention is best illustrated in detail in Fig. 2, although it is shown applied in Fig. 1. Its back is formed by the cloth A. Its front is formed by a piece of cloth 1 which may be of single or double thickness and which is by preference of the same character and color as the cloth A, and in ordinary overalls it is convenient to sew this front piece 1 to the back piece A by ordinary stitches passing through the two pieces as shown. As illustrated, the front piece 1 is cut in the shape of a trapezoid, its upright side edges being parallel, its upper end at right angles to its side edges, and its lower end inclining downward to the left; but this specific shape is not necessary although I prefer it. Beginning at the upper right-hand corner 2, the right edge 3 is stitched as at 4 (two rows of stitching herein shown to the rear cloth A, and the stitching is carried down to the corner 5 beneath; then it is carried along the lower end 6 as at 7, to the lower left corner 8, and thence upward along the left edge 9 as at 10, terminating at the point 11 and preferably being reinforced by stout cross stitching 12 as indicated by the heavier dotted lines. From this point to the upper left corner 13, the edge 14 of the front cloth 1 is not stitched to the rear cloth A, but the lines of stitching are carried along on the front 1 as indicated at 15 to give this portion of the device greater strength, and doubtless the cloth will be turned in over the edge 14 and stitched to itself so as to be double along what is to form the open mouth of one of the pockets or one of the compartments of the whole pocket. From the corner 13 to the corner 2 across the upper end of the pocket, the upper

end of the piece of cloth numbered 1 is left a little full and is attached to the cloth A only at two points 20 and 27 between said corners as described below; whereas the 5 lines of stitching 16 are carried across the fabric 1 and the upper end of the latter may be inturned and doubled as suggested for the pocket-entrance 14. A main line 17 of bias stitching is then run from the corner 10 13 to the corner 5, being made heavier or doubled at both ends so as to reinforce the pocket at its corners, and the upper reinforce 18 stands above the pocket entrance 14. A second bias line of stitching 19 sub- 15 stantially parallel with the first is then carried from the point 20 on the upper end of the fabric 1 downward to the point 21, where it is omitted to the point 22 and then taken up again and carried thence down- 20 ward to the point 23—this line together with the line 17 producing a long oblique pocket 24 whose mouth is indicated at 25. Obviously the bias line of stitching 19 near its upper end crosses the horizontal lines of 25 stitching 16, and while the latter are through the front thickness 1 of cloth only, the line 19 passes through both the thicknesses 1 and A, as does the line 17, so that the pocket is firmly attached to the goods. An oblique 30 line of stitching 26 starts from the point 27 and is carried down at an angle to the line 19 which it meets at the point 21, thereby forming a triangular compartment or pocket 28 whose entrance or mouth is indicated at 29. Parallel with the line 26 a second line 30 starts from the upper right-hand corner 2 and is carried down to the point 22, being made quite heavy or reinforced at 31 at the upper right-hand corner of the pocket, 40 and passing through both thicknesses 1 and A, as does the stitching 26. Thereby is produced a long oblique pocket 32 for a pencil or other small article, the mouth of this pocket being indicated at 33. Across its 45 lower end—which opens into the long pocket 24—the line 19 of stitches is interrupted so that the line 17 of stitches must form the lower end of this pocket 32. The long pocket 24 is obviously for a longer pencil or for the 50 pencil when it is new, whereas after it becomes shorter it can be put into the pocket 32. The triangular pocket 28 may be used for matches. The large triangular pocket 38, whose entrance or mouth is indicated at 55 14, may receive the ruler or could, in fact, carry small change, the pipe, or other articles which the user may not care to have stick out of his pocket. The trapezoidal shape of the front piece 1 of fabric is now 60 seen to have its use, for its inclined lower end 6 makes this large pocket 38 deeper at the corner 8 and thereby increases its capacity.

I have spoken herein of stitching, and 65 doubtless the pocket will be formed by that

means under ordinary circumstances; but I reserve the right to employ any other means of attaching the pocket 1 to the fabric A, and it is possible that other means might be desirable if the pocket itself were not of 70 cloth. In this last respect, also, I do not wish to be limited. Furthermore the bias pocket 24 might run from the corner 2 to the corner 8 if it were desired that it have greater depth, and then the oblique pocket 75 32 would run from the corner 13 to the bias pocket. This might be accomplished by inclining the lower end 6 in the opposite direction, or by leaving it as it is shown and inclining the lines 17, 19, 26 and 30 in 80 the opposite direction. I have spoken of the sub-divisions 24, 28, 32 and 38 as "pockets" herein, whereas in reality they are sub-divisions or compartments of the main pocket which as an entirety is formed of the front 85 sheet of fabric 1 stitched to the goods A. I am, of course, aware that pockets have been sub-divided by lines of stitching and otherwise, and that they have been reinforced at the points of greatest strain; but I 90 consider it especially advantageous to have a long, narrow, and rather small pocket such as 24 passing obliquely through the device, and another such as 32 intersecting it; and I 95 find by experience that if pencils are placed in both of these, the shorter pencil will rest against the other and neither will so readily become lost out. While I have spoken of pencils, it is obvious that any tools or implements of suitable size might be substituted therefor, and to this end the proportions of parts may be varied with considerable 100 freedom. While I have illustrated the 105 pocket as applied to the apron A of a pair of overalls, it is quite obvious that it could be applied to the overalls themselves, to the cloth of a coat, or to any other garment or piece of cloth.

What is claimed is:

1. A quadrilateral pocket having a long compartment extending obliquely from corner to corner thereof and open at its upper end, and another compartment extending from the remaining upper corner to and opening into the first-named compartment. 110
2. The herein described pocket of trapezoidal configuration comprising an oblique compartment extending from one upper corner to the opposite lower corner, a second oblique compartment extending from the remaining upper corner obliquely downward in the opposite direction and opening into the first-named oblique compartment, a triangular compartment between these two compartments, and a fourth compartment 120 beneath the first-named oblique compartment and opening out the side of the pocket. 125
3. The herein described compartment pocket composed of a front layer of material, a rear layer, a line of stitching around 130

the periphery of the front layer and connecting it to the rear layer excepting where the mouths of the various compartments occur, and other lines of stitching through 5 both layers and producing one bias compartment, an oblique compartment running into the bias compartment, and a triangular compartment beneath the bias compartment

and opening out the side of the front layer, substantially as described.

10

In testimony whereof I affix my signature in presence of two witnesses.

DAVID S. BERNSTEIN.
